Kooper Polymers Magnetic Carpenter Pencil Clip with pencil, by Kooper Polymers, Manufacturer: Polymers West, ASIN: B0845VPSGQ, online at Amazon.com, Date First Available: Jan. 23, 2020.*

Primary Examiner — Elizabeth A. Albert

(74) Attorney, Agent, or Firm — Dunlap Bennett & Ludwig, PLLC; Brendan E. Squire

(57) **CLAIM**

The ornamental design for a carpenter pencil clip, as shown and described.

DESCRIPTION

FIG. 1 is a perspective view of the carpenter pencil clip showing my new design;

FIG. 2 is a right elevation view thereof;

FIG. 3 is a left elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a perspective exploded view thereof; and,

FIG. 9 is a perspective in use view thereof with environment. The broken lines in FIG. 9 showing the carpenter pencil clip in use illustrate environment and form no part of the claim.

1 Claim, 4 Drawing Sheets
